UNITED STATES PATENT OFFICE.

HOBART B. IVES, OF NEW HAVEN, CONNECTICUT.

DESIGN FOR A BEAD-ENGAGING THIMBLE.

SPECIFICATION forming part of Design No. 28,859, dated June 14, 1898.

Application filed December 31, 1897. Serial No. 665,241. Term of patent 14 years.

To all whom it may concern:

Be it known that I, HOBART B. IVES, of New Haven, in the county of New Haven, and in the State of Connecticut, have invented a certain new and original Design for a Bead-Engaging Thimble for Adjustable Window-Bead Fasteners; and I do hereby declare that the following is a full, clear, and exact description thereof, reference being had to the accompanying drawings, in which—

Figure 1 shows, on an enlarged scale, a plan view of the thimble formed in accordance with my improved design; Fig. 2, a view of the same in side elevation; Fig. 3, a view of a section of the same on line $x-x$ of Fig. 1, and Fig. 4 a view of a section of the same on line $y-y$ of Fig. 2.

The essential feature consists of the unitary design as made the subject of description and illustration.

As shown in the accompanying drawings, the thimble formed in accordance with my design has a tapering body A, cup-shaped in general form, with its bottom or inner end in the shape of a flat table A', with a transverse slot a.

Around the upper larger end of the body A is an annular outwardly-extending lip or

flange a', while extending along down the outer sides of such body are the longitudinal ribs $a^2 a^2 a^2 a^2$, four in number, two of such ribs being situated diametrically opposite each other at the ends of a diametrical plane through the body A at right angles to the line of greatest width of the slot a, and the other ribs being arranged just beyond the opposite ends of said slot.

The lip or flange a' is arranged to extend out over the adjoining ends of ribs $a^2 a^2 a^2 a^2$, so as to conceal the same, as the thimble is seen in plan view, as shown in Fig. 1, and has a continuous or unbroken inner periphery or edge.

Having described my invention, what I claim as new, and desire to secure by Letters Patent, is—

The design for bead-engaging thimble for adjustable window-bead fasteners, as herein shown and described.

In testimony that I claim the foregoing I have hereunto set my hand this 3d day of December, A. D. 1897.

HOBART B. IVES.
